UNITED STATES PATENT OFFICE.

MICHAEL OSTROSKI, OF CONISTON, ONTARIO, CANADA.

SCAFFOLD.

1,349,093.

Specification of Letters Patent. Patented Aug. 10, 1920.

Application filed March 14, 1918. Serial No. 222,419.

To all whom it may concern:

Be it known that I, MICHAEL OSTROSKI, a subject of the King of Great Britain, residing at Coniston, Province of Ontario, 5 Dominion of Canada, have invented a new and useful Scaffold; and I do hereby declare the following to be a full, clear, and exact description of the invention, such as will enable others skilled in the art to which it 10 appertains to make and use the same.

The present invention relates to a sectional and knock-down scaffold which is adapted for use in the erection of all kinds of buildings and structures, the device embodying novel features of construction whereby it can be assembled in such a manner as to meet the requirements of any conditions which may be encountered in ordinary practice.

20 Further objects of the invention are to provide a sectional scaffold which is comparatively simple and inexpensive in its construction, which can be easily and quickly assembled or taken apart, which provides a 25 rigid and safe construction, and which can be used in connection with both large and small pieces of work.

With these and other objects in view, the invention consists in certain novel combinations and arrangements of the parts as will 30 more fully appear as the description proceeds, the novel features thereof being pointed out in the appended claims.

For a full understanding of the invention, reference is to be had to the following description and accompanying drawings, in which:—

Figure 1 is an end view of a portion of a scaffold constructed in accordance with 40 the invention.

Fig. 2 is a side elevation of the lower portion thereof.

Fig. 3 is a horizontal sectional view on the line 3—3 of Fig. 1, showing a portion 45 of the platform.

Fig. 4 is a transverse sectional view through the platform on the line 4—4 of Fig. 3.

Fig. 5 is an enlarged sectional view on 50 the line 5—5 of Fig. 1, showing the manner of securing the lowermost upright unit to the base.

Corresponding and like parts are referred to in the following description and 55 indicated in all the views of the drawings by the same reference characters.

The upright members of the scaffold are formed by assembling a series of upright units 1 in a superposed relation to each other, the number of units employed depending upon the height to which the scaffold may be carried. Each of the upright units 1 is provided at its lower end with a foot plate 2 and at its upper end with a head plate 3, the foot plate 2 of each upper unit being designed to rest upon the head plate 3 of the lower unit and to be secured thereto by bolts 4, said bolts passing through corresponding openings in the two plates. The ends of the head plate 3 are preferably returned upwardly at 3^a so as to fit around the edges of the foot plate 2 of the superposed unit, thereby holding the superposed upright securely in position even though the bolts may become loose.

The bottom of the lowermost unit 1 is secured to a base 5, said base being provided with flanged strips 6 which fit over the edges of the foot plate 2 and having the ends thereof bent upwardly and inclined to provide braces 7 which engage the sides of the upright 1 and are secured thereto by a transverse bolt 8 which passes through a suitable opening in the upright. The base 5 provides an extended bearing surface for engagement with the ground, and the bolts 9 which secure the foot plate 2 of the upright 1 to the base may be of sufficient length to pass through the base and engage spurs 10. When the scaffold is supported upon a dirt foundation, these spurs will prevent slipping at the base thereof. However, if the scaffold is erected upon concrete, the spurs 10 may be omitted and short bolts 9 employed.

Each of the upright units 1 is provided with a series of brackets 11 which project laterally upon opposite sides of the upright and are preferably adjustable thereon so as to be set at different elevations. In the present instance the brackets 11 are shown as slidable upon the uprights and as each provided with a pair of openings 12 adapted to be brought into registry with any selected set of notches 13 in the edges of the 105 upright. Each of the brackets is also provided with an upstanding ear 11^a which is provided with a perforation 14 adapted to register with any selected one of the openings 15 in the upright. Brace strips 16 are 110 employed to secure the uprights to adjacent parts of the building or other struc-

tures so as to tie the scaffold to the building in the usual manner. In the present instance the brace 16 has a T-shaped formation, the transverse head thereof being provided with openings 17 by means of which it can be secured to the structure by suitable fastening members, while the other member is provided with openings 18, any selected one of which can be engaged by a bolt 19 which also passes through one of the openings 12 of a bracket 11 and engages one of the notches 13 of the upright. The bolt 19 thus serves to secure the members to the bracket and to lock the bracket in an adjusted position upon the upright. These braces 16 can be used wherever it is found necessary to tie or connect the scaffold to the building.

The platform is shown as formed of a series of boards 20 which have the extremities thereof fitted in corresponding sockets in cross heads 21. Removable pins 22 pass through the cross head and engage the ends of the boards 20 to prevent the boards from pulling out of the sockets and becoming disengaged from the cross head. The cross head 21 is provided with rearwardly projecting wings 23 which are spaced apart so as to straddle the upright 1 and rest upon the projecting ends of one of the brackets 11. A bolt 24 passes through the ear 11^a of the said bracket and one of the openings 15 of the upright, said bolt also engaging the cross head so that it serves both to hold the bracket in an adjusted position and to secure the cross head to the upright. The extremities of the wings 23 may terminate in down-turned lips 25 which extend downwardly over the sides of the bracket and serve to prevent the cross heads from pulling away from the bracket when there is any weight upon the platform. The platform and bracket can be readily raised and lowered upon the standard and set at any desired elevation thereon. It will be understood that the different parts of the scaffold are similar and interchangeable, thereby enabling them to be assembled to produce either

a small or a large scaffold, and to be arranged in such a manner as to meet any of the conditions which are encountered in ordinary building practice.

Having thus described the invention, what I claim as new and desire to secure by Letters Patent, is:—

1. A sectional scaffold including similar and interchangeable upright units, each of which is provided at the bottom with a flat foot plate and at the top with a corresponding head plate, fastening members connecting the foot plate of one upright unit to the head plate of another upright unit, brackets projecting from the uprights, a cross head constructed to engage one of the brackets, and a platform mounted upon the cross head.

2. A sectional scaffold including similar and interchangeable upright units, each of which is provided at the bottom with a flat foot plate and at the top with a corresponding head plate, opposite edges of the head plate being returned to fit over the foot plate of a superposed unit, fastening members for connecting the head plates and foot plates of superposed units, a platform, and means for mounting the platform upon the upright units.

3. A sectional scaffold including similar and interchangeable upright units, each of which is provided at the bottom with a flat foot plate and at the top with a corresponding head plate, means for securing the head plate of one unit to the foot plate of a superposed unit, a base plate arranged under the foot plate of the lower unit, removable spurs for the base plate, and fastening members securing the foot plate of the lower unit to the base plate and also engaging the spurs.

In testimony whereof I have signed my name to this specification in the presence of two subscribing witnesses.

MICHAEL OSTROSKI.
